JOHN R. KUNZELMAN, OF GORDON, WISCONSIN.

INSECT-ESCAPE FOR SCREENS.

1,020,830.

Specification of Letters Patent. Patented Mar. 19, 1912.

Application filed January 14, 1911. Serial No. 602,545.

To all whom it may concern:

Be it known that I, JOHN R. KUNZELMAN, a citizen of the United States, and a resident of Gordon, in the county of Douglas and State of Wisconsin, have invented a new and Improved Insect-Escape for Screens, of which the following is a full, clear, and exact description.

The invention relates to screens, particularly door and window screens, and has for an object to provide an escape screen whereby flies or the like can find exit from a chamber and are prevented from entering the chamber from the outside.

For the purpose mentioned use is made of a screen provided with apertures and a closure mounted on the frame of the screen to close the said apertures with means for normally holding the closure away from the apertures.

Reference is to be had to the accompanying drawings, constituting a part of this specification, in which similar characters of reference denote corresponding parts in all the views, and in which—

Figure 1 is a fragmentary side elevation of a screen equipped with my device, parts being broken away to disclose the underlying structure; Fig. 2 is a sectional view on the line 2—2 in Fig. 1, and showing the closure in normal position; Fig. 3 is a similar view but showing the closure disposed to close the apertures in the screen; and Fig. 4 is a perspective view disclosing a portion of the apertured screen.

Referring more particularly to the drawings I provide a screen 10 secured to a frame 11 constituting a part of the screen, and formed in the screen 10 are a plurality of apertures 12, with strips of wood 13, secured to the frame 11 on both sides of the apertures. A closure member 14 is hingedly mounted to depend from the frame 11 and a spring catch 15 provided with a right angled holding end 16 is secured to the frame 11 and adapted to normally engage the closure 14 to hold the same away from the apertures 12 as will be seen in Fig. 2.

When there are flies or insects on the inner side of the screen, the closure 14 is secured by the catch 15 as shown and as in-

sects naturally move toward the upper end of a screen, they soon find exit through the apertures 12. If it is desired to prevent any insects from entering a chamber 55 through the apertures 12 in the screen, the closure 14 is released from the catch 15, and gravitationally assumes a position to close the apertures as will be seen in Fig. 3, thus preventing the insects from entering 60 through the said apertures.

From the foregoing description it will be seen that a substantial and efficient escape for insects is provided and the same is also adapted to prevent the insects from entering 65 a room or chamber through the screen.

By painting the closure a bright color on the lower side thereof, it would serve as an attraction for flies or insects, and although for the purpose of describing my insect 70 escape for screens, I have shown a particular construction, it will be understood that the scope of the invention is defined in the appended claim.

Having thus described my invention, I 75 claim as new and desire to secure by Letters Patent:

In a device of the class described, a frame, a screen secured to the frame, strips extending across the frame and secured to the 80 ends thereof, the said strips being on one side of the screen, a plurality of apertures within the screen and between the said strips, a closure member hinged on the said frame, the screen being positioned between the strips and the closure member, the said member in normal position lying closely adjacent the said strips whereby the openings in the screen are covered, a spring catch carried by the said frame and remote from the 85 said closure member whereby the said member may be moved on its hinges to uncover the openings in the screen and may be held in such position by engagement with the spring catch.

In testimony whereof I have signed my name to this specification in the presence of two subscribing witnesses.

JOHN R. KUNZELMAN.
